UNITED STATES PATENT OFFICE

156,583

RADIO CABINET

Elwood F. Tresner, Anacortes, Wash.

Application August 10, 1948, Serial No. 148,030

Term of patent 3½ years

(Cl. D56—4)

To all whom it may concern:

Be it known that Elwood F. Tresner, a citizen of the United States, residing at Anacortes, Washington, has invented a new, original, and ornamental Design for a Radio Cabinet, of which the following is a specification, reference being had to the accompanying drawing, forming a part thereof, in which

Fig. 1 is a perspective view of a radio cabinet, showing my new design;

Fig. 2 is a front elevation of the same;

Fig. 3 is a top plan view of the same;

Fig. 4 is a front perspective view showing the radio cabinet as it appears when in open position.

Fig. 5 is a cross-sectional view taken along the line 5—5 of Fig. 4.

The characteristic features of my design reside in the portions shown by means of full lines in the drawing.

I claim:

The ornamental design for a radio cabinet, as shown and described.

ELWOOD F. TRESNER.
